JOHN LAWLER MORGAN, OF CAMDEN, NEW JERSEY, ASSIGNOR TO JESSE SATENSTEIN,
OF NEW YORK, N. Y.

COUNTER

Application filed March 9, 1929. Serial No. 345,728.

The present invention relates to electrically operated counters to be attached to machines for the counting of movements of a part thereof or the counting of articles moving along a course.

An object of the invention is to provide an apparatus of such construction that an accurate and dependable count of movements or articles may be made thereby.

10 A further object is to provide an apparatus for counting in the manner set forth which may be readily applied to machines of various descriptions for counting and to various parts of such machines.

15 A still further object is to provide an electrical apparatus for counting in the above manner, a switch which is adapted to take advantage of the deflection from a straight course of articles moving along said course 20 for the operation of said apparatus.

The invention is particularly applicable to the counting of such articles as sheets of paper moving along a course, as in a folding machine, said course having a bend therein, 25 and consists in an electric circuit including therein a counter operating means, and a switch operable by movement of articles or mechanism.

The switch may be made more sensitive by 30 having one of the terminals flexibly mounted and one of the contacts or terminals may be made of carbon to prevent the production of arcs and a consequent welding of the contacts together and thereby destroying its utility.

35 The counter operating means may be electro-magnetic in character and impedance may be reduced or eliminated altogether from the coil of the electro-magnet by shunting a lamp across the circuit between the switch and the electro-magnet.

40 In the application of this apparatus to a machine such as a "Cleveland folder" where sheets of paper pass along a course and are deflected downwardly therefrom to the folding mechanism, advantage

45 may be taken of the "pickup" of the rear ends of the sheets so passing, as they are deflected from the straight line course, to increase the accuracy of the count. Other peculiarities of the movement of the sheets 50 in their movements when fed between the

racks and against an abutment by feed rollers may be taken advantage of to insure accuracy of the count.

The principles of the invention will be set forth in an embodiment thereof as applied to a Cleveland folder, and in order to more clearly appreciate the said principles, reference may be had to the accompanying drawings in which,

55 Figure 1 is a more or less schematic view showing the conveying rollers of a Cleveland folder together with a fragmentary portion of the folding mechanism and showing the switch of the present embodiment of my invention connected therewith.

60 Figure 2 is a section through the switch casing illustrating the switch itself and the member for attaching the same to a support.

65 Figure 3 is a bottom plan view of the switch casing and mechanism.

70 Figure 4 is a plan view of a counting mechanism and the operating mechanism associated therewith with the casing removed.

75 Figure 5 is a section through the casing further illustrating the counter mechanism in connection with the operating mechanism.

80 Figure 6 is a perspective view of the casing showing the counter indications and a window for the observation of the lamp and a switch protruding from the casing.

85 Figure 7 is a diagrammatic view showing the scheme of wiring with the switches, counter mechanism and the lamp in circuit.

Figure 8 is a fragmentary detail view of a variation in the switch mechanism represented in Figures 2 and 3.

90 The invention as previously stated is particularly applicable to a paper folder and to such other mechanism in which great sensitivity of the apparatus and accuracy of the count is required.

95 Great difficulty has been experienced in providing an electric counter which is dependable in operation and sufficiently sensitive to count sheets as they pass along the course.

100 The illustration in Figure 1 shows the

manner in a paper folding machine in which the sheets are carried across the feed table and delivered into the folding mechanism. Sheets, under these conditions, are not infrequently conveyed in an overlapping relation one to the other so that the counter depending for its operation merely upon the contact of a sheet with an actuating means will be inaccurate in the extreme. For this reason electrical counter operating mechanism has been largely discarded in the application of the mechanism to a folding machine.

I take advantage of certain characteristics of the movement of the sheets in being fed from the table to the folder one of which is the fact that as the sheets are deflected from the horizontal course and fed to the folding mechanism, the rear end of each sheet will be lifted off of the conveyor rollers and will have a certain "kick up" at its rear end.

Referring first to Figure 7 of the drawings; 10 designates an electric circuit which may be fed from any suitable source as from main wires through leads 11 and this circuit has included therein an electro-magnet 12 and a switch 13, the former being arranged for operation of a counter and the latter for actuating the electromagnet incident to the movement of the sheets to be counted thereby. The counter is designated by the numeral 14 and may be suitably connected with the armature of the electro-magnet for operation thereof.

15 A manual switch 15 is placed in the circuit by means of which the mechanism may be rendered inoperative at will. Across the electro-magnet 12, I shunt a circuit 17 including a lamp 16, which tends to reduce the impedance in the coil of the electro-magnet. The counter is of any usual type whereby each complete reciprocation of a crank arm 18 will register one count on the dials contained therein, the same being arranged for 20 counting up to a predetermined number.

Referring now to Figures 2 and 3, which illustrate the switch 13, 19 indicates a supporting block of fibre or other insulating material on which are mounted the contacts 20 and 21, the former being preferably of carbon and is supported by an arm 22 of conductive material to which one of the conductors of the circuit is connected as by the screw 23. This contact member is preferably stationary and is normally in constant contact with the contact member 21 which is flexibly mounted and adapted to rest by gravity upon the contact 20. The movable contact 21 is preferably of metal and is pivoted to supports 24 having bearing apertures 25 in their dependent lower ends. The contact 21 is electrically connected with the other terminal of the circuit through one of the supports 24 as at 26 and the conductor 27 which may be of phosphor-bronze is con-

tinued as at 27 and connected with the contact member 21 to provide a yielding member positively forcing the contact 21 against the contact 20. This member 27 may have substituted therefor a spring such as is illustrated at 27^a in Figure 8 of the drawings, in which case the member 27 is omitted.

An extension 28 of non-conductive material may be attached to the contact 21 in any suitable manner as being held thereon by glue or by clips or other suitable holding means. This member is designed to project into the path of travel of elements to be counted and by contact thereof with such elements, the switch connection is momentarily broken causing registration in the counting device of the passing of the element. This member 28 may be of any suitable material and I have found a strip of paper serves the purpose quite well. The sensitiveness of this switch and the positive-ness of its operation depends in a considerable measure on the flexible mounting of the arm 21 by means of the pivoted connection at 25 with the supports 24.

The switch mechanism here described may be protected by an enclosing casing 29 mounted on the insulating block 19 to which is secured or formed integral a suitable supporting device 31 for the switch which may be attached to any convenient portion of the machine as to a rod 30 extending transversely thereof as indicated in Figure 1 of the drawings. This member 31 may be constructed so as to be conveniently attached to a rod as referred to above by forming the same with a kerf 32 having a constricted neck 33 and a circular portion 34 into which the set screw 35 may be projected as stated above.

In Figure 1 of the drawings, 36 represents a feed table and 37 a portion of the folding mechanism. The sheets of paper, in a machine of this character, are fed along by the feed rollers 39 and are passed between the rollers 38 at an angle to the path of travel defined by the rollers 39 on the feed table. In making this turn, the rear end of the sheet will "kickup" as indicated at 40 and by properly placing the switch mechanism the member 28 will be forced upwardly by the kickup of the rear end of the sheets as they pass between the rollers 38. In this manner an accurate count of said sheets may be made regardless of whether the sheets are fed along by the elements 39 separately or in an overlapping relation one to another. The sheets fed between the rollers 38 pass between the rack members 41 and 42 coming in contact with an abutment 43 whereupon the sheets will buckle downwardly toward the folding rollers 44 and finally be clipped therebetween and folded as indicated in Figure 1. This characteristic of the movement of the sheets may also be taken advantage of to

provide an accurate count by suitably mounting the switch 13 relative thereto.

Referring now to the counting mechanism and the operating mechanism associated therewith as illustrated in Figures 4 and 5 of the drawings. The crank arm 18 of the counting mechanism 14 is connected through the link 45 with the armature 46 of the electro-magnet 12 and one complete oscillation 10 of the arm 18 will make one complete count in the counting device, the stroke to the right being made by the energizing of the electro-magnet and that in the opposite direction by the force of the contractile spring 47 connected at one end to the armature and by the other end to a screw or other suitable support 48. This screw may be arranged at various angles to adjust the tension of the spring 47 or may be located at a slant and adjustment of said tension may depend on the position on the end of the spring connected to the spring 48 along the shank thereof.

The lamp 16 is shunted into the circuit and a part of the energy supplied by the circuit 25 is passed through the lamp, as clearly indicated in Figure 7 of the drawings; the shunt being connected at one end to the circuit at 49, the other terminal of the shunt being connected with the circuit at 50. The provision 30 of a lamp in this connection serves the double purpose of indicating the working condition of the mechanism and of cutting down impedance, insuring the sensitive working of the mechanism. When the light is glowing 35 steadily, no count is being made and when the light is glowing intermittently, the device will be known to be functioning properly.

A window 16^a is provided in the casing therefore from which the lamp may be observed and a second window 14^a is provided adjacent thereto for observation of the counter mechanism.

I have found that a closed switch in certain situations gives better results than an 45 open switch and the invention as herein described contemplates such a closed switch although an open switch may be substituted therefor under certain circumstances without departing from the spirit of the invention. While the closed contact is sufficiently 50 sensitive for the purposes of the present application of the invention, it is not super-sensitive to the extent that ripples in the paper will cause a count. The provision of 55 a carbon contact in the switch mechanism 13 prevents the forming of an arc between the contacts and the consequent welding of the contacts together.

By the use of a device of this character, 60 I have found that a very accurate count may be made in a situation such as outlined above and where sensitiveness of the apparatus is necessary owing to the nature of the articles to be counted. It will appear, however, that 65 the invention may have much wider appli-

cation than to the counting of sheets of paper moving along a course or other articles of similar nature and may be adapted to the counting of movements of mechanism or of other elements consecutively moving past the 70 arm 28. It is also to be understood that the switch may be adapted to make its count on other parts of the machine than that illustrated. I do not wish, therefore, to be limited to any specific embodiment of the invention or to any particular application 75 thereof to a machine.

I claim:—

1. In combination with means for conveying sheets of paper along a course having 80 a turn therein, and means for causing the rear end of the sheets to kick up in making the turn, of a switch mechanism in circuit with counter operating means, said switch having terminals one of which is operated 85 by the kick up of said sheets.

2. In an organization for counting single moving sheets, means to cause the sheet to kick-up one edge, and circuit controlling 90 means positioned for engagement by said kicked-up edge.

3. In an organization for counting single sheets moving along a pre-determined plane, rollers engaging said sheets and changing the course of travel of said sheet from said plane 95 and causing a kick-up of one edge of said sheet, and circuit controlling means positioned for engagement by said kicked-up part.

In testimony whereof I have signed my 100 name to this specification.

JOHN LAWLER MORGAN.
